UNITED STATES PATENT OFFICE.

JOHN B. ODELL, OF CHICAGO, ILLINOIS, ASSIGNOR TO THE PRINTING TELEGRAPH COMPANY OF ILLINOIS.

TYPE SETTING AND DISTRIBUTING INDICATOR.

SPECIFICATION forming part of Letters Patent No. 392,358, dated November 6, 1888.

Application filed August 22, 1887. Serial No. 247,532. (No model.)

To all whom it may concern:

Be it known that I, JOHN B. ODELL, a citizen of the United States, and a resident of Chicago, in the county of Cook and State of Illinois, have invented certain new and useful Improvements in Type Setting and Distributing Indicators, of which the following is a full, clear, and exact description, reference being had to the accompanying drawings, and to the letters 5 of reference marked thereon, which form part of this specification.

My invention relates to the work of composing and distributing matter in the art of printing, and, having for its object to so facilitate and 15 simplify such work that unskilled labor may be employed therein, consists in the matters hereinafter set forth, and pointed out in the appended claim.

My present invention embraces the employment, 20 in combination with a subdivided type-holder or compositor's case, of mechanical devices operatively arranged and adapted to indicate the types to be successively taken from the said holder or case or distributed therein 25 by the compositor in the work of setting up or distributing matter. Each of the type-subdivisions of the said holder or case is provided with an indicator capable of being moved from its normal position through the action of a 30 key forming part of a key-board located adjacent to said case and connected therewith. The said keys respectively represent the particular types for which each subdivision of the holder or case is provided, and are intended 35 to be successively manipulated by an operator (before whom the copy is placed) similarly after the manner of manipulating the key-board of a type-writing machine. In practice, as each indicator is raised in similar 40 order, the compositor takes from or deposits a type within each particular subdivision indicated, at the same time carrying the indicator back to its normal or operative position. In the work of composing it is only necessary for him 45 to pick up the types and place the same within his "stick" in the order in which the indicators are caused to be raised, and in distributing he deposits the type within the subdivisions, and in the order indicated, from 50 matter usually held within his hand. The

preferred manner of practically carrying out my said invention is shown in the accompanying drawings, in which—

Figure 1 is a view in perspective illustrating the type-holder B sustained by a frame, A, which contains the indicator-operating mechanism. Fig. 2 is a sectional view taken vertically through the said frame and type-holder, illustrating the operative arrangement of the keys and indicators. Fig. 3 is a broken 60 plan view particularly intended to illustrate the arrangement laterally of the key-arms within the frame A. Fig. 4 is an enlarged detail intended to illustrate the operative arrangement and connection of the keys and indicators. Fig. 5 is a plan view of the indicator, the same being shown detached from the type-holder D.

Referring to the several figures of the drawings in detail, within the frame A a series of 70 key-levers, C, vibratory held by bearings c, are provided at one end each with a stem, c', having at its extremity a knob, c'', which represents the type intended to be contained within one of the subdivisions of the case B, which 75 is sustained by said frame A. The other end of each of said key-levers operatively connects with a movable rod, C', which passes through the body of said case to operative connection with an indicator device, D, desirably attached thereto. The end of the said rod C' opposite its point of connection with said key-lever is adapted to engage with and raise a movable plate, d, forming part of the said indicator D when actuated by the key-lever C through the downward movement of the key-stem and knob c' c''. When the knob is freed from the pressure manifestly applied to operate the key, the said rod, being provided with a spring resistance, e, which tends to hold 80 it in a direction from the said plate, returns to its normal position, as shown in Fig. 4. The spring e upon the rod C' likewise extending through said rod, which is intended to be in constant engagement with the end of the key-lever C, a downward tension upon the end of the said lever serves to depress the engaging end of the said lever, and thus keep its opposite or knob end in raised operative position. 95

The indicator device D, which is desirably 100

fixed to the body of the case B, I prefer to construct and operate as follows: The movable plate d is pivotally connected to a lower section, d' , which is fixed to the case B. The 5 bearings p of the said two sections are so arranged with relation to each other, as shown in Fig. 5, that a coiled spring, d^2 , located around the securing-pin d^3 , exerts a strain laterally upon plate d in the direction of and 10 against the section d' . When the plate has been moved from its normal position through the action of the rod C, the strain of the spring d^2 , bringing about considerable friction between the bearing portions of the two parts d d' , 15 causes the plate d to remain in its raised position after the rod C has returned to its original position and until moved to its normal or closed position by the compositor, who would

ordinarily push the same down in picking up or distributing the type.

Having thus sufficiently described my invention, I claim as new and desire to secure by Letters Patent—

The combination of a subdivided type-holder or compositor's case, a suitable number of indicators connected therewith and adapted to indicate the types intended to be contained within the respective subdivisions thereof, and a corresponding system of keys mechanically connected with said indicators and adapted to operate the same, substantially as herein described.

JOHN B. ODELL.
